APPARATUS FOR CLEANING STRIP METAL

George M. Croft, Pittsburgh, Pa., assignor to
 Blaw-Knox Company, Pittsburgh, Pa., a corporation of New Jersey

Application March 20, 1940, Serial No. 325,081

2 Claims. (Cl. 15—7)

This invention relates to the surface treating of strip metal, and is for an apparatus for effectively cleaning the surface of a continuously moving strip by a succession of alternate scrubbing and liquid spraying operations with rinsing and drying of the strip at certain stages in the treatment.

In treating moving metal strip particularly where the strip is to be moved at a high rate of speed such as 1500 to 3000 feet per minute, it is apparent that even a few thousandths of an inch thickness of liquid film on the surface of the strip will amount to a large quantity of liquid carry-over within a short period of time, thus emphasizing the need for a practical method of, in effect, restricting each liquid treating step and preventing carryover of a film of treating fluid from one operation to the other. Another consideration is the fact that an ordinary drying operation may be employed to remove relatively clean solutions, but that concentrated as well as dilute solutions thus removed leave a solid residue on the surface of the strip. In the case of a concentrated solution, this results in the loss of valuable chemicals; furthermore, solid residues, if allowed to remain on the strip, tend to result in a loss of surface uniformity and brightness.

The object of the invention is to provide an apparatus for cleaning metal strip in which both mechanical scrubbing and chemical cleaning and final washing and drying are economically and effectively accomplished, and with practically no carry-over of chemical solutions used in one stage to another, and without the carry-over of appreciable amounts of solids on the surface of the metal resulting from the evaporation of a film of such liquid. According to this invention, suction devices are used at certain stages of the treatment in order to remove any adhering film of liquid on the sheet, thereby avoiding the carry-over of the liquid film from one stage of the treatment to another, and also avoiding the deposit which the evaporation of such a film, if not removed, would leave.

In the drawings:

Figure 1 is a vertical view in elevation and in partial section of a complete layout somewhat diagrammatically illustrated for treating continuous strip in accordance with the principles of the present invention;

Figure 2 is an enlarged front end view in sectional elevation of a detail of the apparatus arrangement of Figure 1;

Figure 2a is a reduced view constituting a con-

tinuation of Figure 2 and showing an apparatus arrangement for producing suction;

Figures 3—6, inclusive are somewhat diagrammatic side views in elevation showing details of liquid removing apparatus.

As shown, for example, in Figure 1, I may employ a coil or reel 5 of strip metal 6. The strip is subjected to a series of cleaning operations or treatments in compartments A to E, inclusive, 10 and is pulled through such compartments or treatment stations at a suitable tension by a pair of motor driven pinch rolls 7. After treatment, the strip may be recoiled or subjected to other treatments as desired. The operation of the present apparatus is not limited to interrupted lengths of strip, but may be and is preferably employed to treat continuous lengths or coiled lengths that are welded together to form a continuous length. The pinch rolls 7 pull the strip past treatment stations at a desired speed, provide a tension suitable to overcome frictional and other losses, and maintain the strip in a substantially horizontal plane during its movement and thus during its treatment.

25 In compartment A, the strip is wet-brushed or scrubbed on both of its sides by roll and brush pairs 10, 12. Previously-used hot washing solution or water is applied in any suitable manner as by jets 13. Thence, clean wash water is applied 30 to both sides of the strip, preferably under a relatively higher pressure, by such means as jets 14 to remove the dirt and grit and the previously-used washing solution. Finally, the thin film of liquid remaining on the surface portions is removed by a suction or vacuum cleaning apparatus 35 30.

The strip enters compartment B dry and as clean as hot water scrubbing can make it and is then subjected to a series of concentrated 40 chemical cleaning solution sprays 18. Additional sprays 23 apply the chemical solution in compartment C while the strip is being brushed and scrubbed by roll-brush pairs 20, 22. Finally, the strip is again washed with a clean washing fluid 45 at 14a and the liquid film removed at 30a. If desired, the step of washing at 14a may be omitted, and the chemical solution instead of wash water removed at 30a, suitable changes in the piping system being made to return the chemical solution 50 for re-circulation.

In compartment D, the chemically cleaned strip is subjected to a series of suitable applications of clean heated wash or rinsing water by sprays or jets 24. In compartment E, the strip 55 is initially subjected to a cleaning jet or spray

application at 14b that is preferably of a high velocity or pressure. Pairs of liquid-film-removing units 30b then remove the liquid to, in effect, finish the operation, in order that the strip 6 is in a thoroughly cleaned and dry state when it leaves compartment E.

The solution supply and application system, shown somewhat diagrammatically in Figure 1, is primarily chosen for the purpose of illustrating the principles of the present invention, and it will be apparent that other suitable arrangements may be employed. The compartment A, the compartments B and C, the compartment D, and the compartment E, have, as shown, collecting tanks for the solutions or fluids employed in treating the strip therein. I have also provided a water settling tank 60 and a chemical solution settling tank 61 that may be employed in a conventional manner to remove sediment and prepare the liquids for reuse. Although I have shown representative pumps, heat exchangers, valves, etc., it will be apparent that they may be rearranged and others may be added in accordance with the requirements of a given installation. The float valves have been given a common designation a; the heat exchangers have been given the common designation H followed by a suffix; the pumps have been designated P followed by a suffix; and the baffling within the tanks 60 and 61 for separating the space into compartments has been indicated as f and g, respectively.

Fresh or clean water is supplied through a main 50 and is pumped by pump P4 through heat exchanger H4, line 51, and heat exchanger H5, line 52, to the clean water sprays or jets 24. Condensate from the heat exchanger H5 flows by gravity through line 53 to heat exchanger H1 that is employed to heat previously-used wash water which is taken off from the wash water settling tank 60 through piping 55 and forced by pump P1 through line 56 and sprays 13. The condensate line 53 also has a branch line 54 that is provided with inlets or orifices b for supplying the settling tank 60 with warm condensate as needed.

Wash water or dilute solution used in compartment A drains off by gravity through lines 57 and 58 to return to the settling tank 60 for reuse. Likewise, liquid taken off by the vacuum suction apparatus 30 flows through line 37 past suction unit 15 through line 45 to the settling tank return line 58.

The chemical solution sprays 18 and 23 of compartments B and C are supplied with chemical cleaning solution by a takeoff 65 from their common collecting tank. The pump P2 moves the takeoff liquid through heat exchanger H2 and into the spray supply line 66. The level of the chemical solution in the collecting tank of compartments B and C is maintained by a float valve a and a solution supply line 68. Pump P3 delivers solution from the chemical solution settling tank 61 through the line 68 as required.

It will be noted that vacuum cleaning devices 30b of compartment E are connected through branch line 31b, vacuum unit 15, line 45b, line 71, and liquid return line 58, to the water settling tank 60, while the cleaning device 30a is connected through line 31a, vacuum unit 15, line 45a, to the chemical solution settling tank 61. A branch line 72 from the collecting tank of compartment D is connected to the washing fluid return line 45b, 71 to supply settling tank 61 with water as needed to compensate for evaporation losses and as controlled by a float valve a.

The water supply line 50 is provided with a branch line 73 that introduces clean wash water into the tanks 60 and 61 through upper inlet openings or nozzles d and lower inlet openings or nozzles e.

In Figures 2 and 2A, I have shown a cleaning unit that may be termed a suction or vacuum unit. An upper suction hood 30 is preferably positioned to extend for substantially the full width of the strip being moved and may be provided with a lower cooperating hood 30'. Both hoods are connected by flexible conduits 36 to a vacuum line 37 of vacuum tank 38. This tank serves to separate air and vapor from the liquid. The gases (air and vapor) are drawn out near the top of tank 38 through pipe 39 by a motor-driven wet-vacuum pump unit 40, while the liquid is constantly removed from the bottom of the tank through pipe 43 by a motor-driven centrifugal pump unit 44. Water for sealing the wet-vacuum pump is supplied by pipe 42, and the air and vapor are discharged to the atmosphere through pipe 41. Pump 44 serves to prevent tank 38 from filling with accumulated liquid and to deliver the liquid to the sewer or to return liquid through lines 45, 45a, or 45b to the settling tanks 60 and 61.

Other apparatus, such as more elaborate means for separating the liquid from the gases combined with a dry vacuum pump, or a further liquid and gas separating stage treating the exhaust from wet-vacuum pump unit 40, may be employed if desired, such substitutions or further refinements being within the scope of the claims.

It will be noted that on Figure 1, I show heated liquid applied to the strip for washing and treating steps, but that cold or unheated liquid is applied at sprays 14, 14a, and 14b, prior to the vacuum removal of liquid by units 30, 30a, and 30b, respectively. These cold sprays are not necessary except where hot treating liquids are employed which would flash into vapor when subjected to a vacuum. Removal of the liquid by evaporation, as has been pointed out previously, is particularly objectionable where the solutions contain dissolved solid constituents such as salts which then remain on the surface of the strip. If the liquid which is in aqueous solution is too hot, its vapor pressure is relatively high and the application of suction for the short period during which the strip is passing the nozzle results in evaporation of the solution such as water rather than in a removal of the liquid film. By applying cold liquid to the strip after the treating operation, but immediately prior to vacuum removal, I am able to cool the solution to a point where detrimental vaporization does not take place, without appreciably cooling the strip itself, which remains at substantially the same temperature after passing between the suction heads. However, under some conditions, particularly after a final washing with pure water, evaporation may be desired, in which case the cold liquid sprays may be eliminated, or where a cool solution is used, heat may be applied thereto by suitable heating elements in the region occupied by the cold sprays shown on Figure 1.

As shown in Figure 2, the hood portions 30 or 30' are provided with transversely-extending brackets 31 that are mounted upon a suitable support frame 34 by adjustable bolt means 32. Springs 33 are held in compression between the frame 34 and the brackets 31 to flexibly mount and support the suction hood portions 30 and 30'.

The bolt means 32 is tightened to compress the

spring 33 when the hood is to be moved away from the strip and is loosened to move the hood towards the surface of the strip.

Although in a preferred arrangement, I employ a pair of upper and lower suction hood portions 30 and 30', it will be apparent, as shown in Figure 5, for example, that single hood portions may be employed and may be staggered in such a manner as to aid pinch rolls such as 7a in supporting or holding the strip 6 in a substantially horizontal plane during its movement.

In the arrangement of Figure 3, I have shown high pressure clean water jets 14 for washing away the previously used solutions and leaving a relatively thin film of clean solution. This, of course, will lessen the burden of the suction apparatus 30. In the arrangement of Figure 4, a forward pair of pinch rolls 7b is employed in co-operation with pinch rolls 7a to hold the strip tightly in position during the suction operation. This arrangement is particularly advantageous to avoid deflection of the strip when an extremely high suction pressure or force is employed. The rolls 7b are preferably drawn closely enough to deflect surplus liquid edgewise to either side of the strip, to thereby leave only a very thin film to be removed by the suction unit 30.

I have found that the speed of the strip should also be considered with reference to the effectiveness of the film removal. If under high speed conditions the amount of liquid to be removed cannot be taken care of by one set of suction nozzles, any suitable number of successive nozzles or suction devices in sequence may be provided as needed.

In Figure 2 I have shown a representative type of suction nozzle arrangement and it will be apparent that other suitable arrangements may be employed depending upon particular requirements and the size and type of impervious material being cleaned. For example, in Figure 6 I have shown an anti-friction non-scratching type of shoe 70 attached to bottom edge portions of the suction nozzles 30 and 30' of Figure 2 by suitable brackets 71 and bolts 72. This figure also illustrates the nature of the suction action upon the fluid film 8. The movement of liquid carried by the strip is partially arrested upon encountering the shoe 70 and the liquid tends to accumulate in such a manner as to prevent contact of the strip with the shoe. Air enters chiefly from the opposite end of the shoe between the shoe and the strip and has a high velocity. This results in the liquid being arrested at the suction nozzle and removed from the strip at the nozzle orifice, as somewhat diagrammatically illustrated in Figure 6. For this reason, I preferably provide the entry portion of the shoe 70 or the suction nozzle with a greater clearance on its incoming side than on its outgoing side. This provides the outgoing side with a narrow orifice to increase the effectiveness of the removing action. The larger size orifice at the incoming side permits a quick removal of the liquid film such that the greater portion of it is removed before the strip has moved past a substantially central point of unit 30.

The hood portions of the suction device 30 are preferably resiliently or flexibly mounted for independent adjustment and also to prevent damage when any solid material, obstruction, or uneven portion of the strip moves therewith.

It will be apparent from the above description that suction or liquid removing vacuum units can be employed along the cleaning line to, in effect,

isolate each cleaning operation to conserve the cleaning fluids and to prevent dilution. The arrangement is such that the liquid film will be removed regardless of the speed of the operation and can be accomplished without the necessity of intermittent pauses. It will be apparent that the strip enters a successive treating station with its surfaces practically free from liquid film, such that the succeeding operation can be more effectively accomplished. It will also be apparent that in such an arrangement where there is no carryover of liquid film, the need for additional successive washing applications has been eliminated as well as the need for additional collecting tanks to provide a re-use of the material washed off by such successive applications. In view of the above considerations, I have been able to effect a high speed treatment of strip whereby it is cleaned at maximum effectiveness and at a minimum expense. It will be also apparent that my invention is not limited to specific apparatus or apparatus arrangements shown, and that various modifications, substitutions, and rearrangements may be made without departing from the spirit and scope of the invention as indicated by the appended claims.

I claim:

1. Apparatus for cleaning continuously moving indeterminate lengths of metal from a coil thereof, which comprises, in combination, means for continuously withdrawing the metal from the coil and for passing the metal continuously through a series of successive treating compartments extending from an intake compartment for the metal to an outlet compartment therefor, means for continuously moving the metal continually in substantially a horizontal plane through all of the said treating compartments, means in the intake compartment for alternately mechanically scrubbing the moving metal and for applying cleaning liquid thereto, followed immediately by means for applying clean wash liquid to the metal, and vacuum instrumentalities for removing substantially completely from the metal all adhering liquid without substantial evaporation thereof from the metal, the said metal thereby passing into a second treating compartment as clean as the mechanical scrubbing can make it, and dry, instrumentalities in the second compartment for applying a concentrated cleaning solution to the metal as it moves through the second compartment into a third compartment, mechanism in the third compartment for mechanically scrubbing the thus-treated metal as it moves therethrough, means intermediate the said mechanically scrubbing mechanism in the third compartment for applying liquid to the metal as the metal is scrubbed, means in the said third compartment following the liquid-applying means and the mechanically scrubbing mechanism for applying clean wash liquid to the metal, vacuum-drying means in the third compartment for removing substantially completely all liquid film from the metal, the said metal passing into a fourth compartment dry and as mechanically clean as the scrubbing can make it, means in the fourth compartment for applying clean wash liquid to the metal, the metal being passed into a fifth, or outlet, compartment, means in the said fifth compartment for applying clean wash liquid to the metal under high pressure, and vacuum-drying instrumentalities operating on the resulting washed metal to remove all liquid adhering thereto, the metal passing from the said compartment dry and in chemically clean condition.

2. Apparatus for cleaning continuously moving indeterminate lengths of metal strip from a coil thereof, which comprises, in combination, a series of successive treating compartments for the strip, extending from an intake compartment for the strip to an outlet compartment therefor, means for continuously moving the strip through the said compartments, means in the intake compartment for alternately mechanically scrubbing the moving strip and for applying hot cleaning liquid thereto, means for heating the cleaning liquid, means for recirculating the cleaning liquid from the said intake compartment through the heating means, mechanism for finally applying clean cold wash liquid to the strip in the intake compartment, vacuum-drying means for the intake compartment for closely applying suction to the strip for removing therefrom substantially all adhering liquid without appreciable evaporation of the liquid from the strip, the said strip thereby passing into a second treating compartment dry and as clean as the mechanical scrubbing can make it, means in the second compartment for applying hot clean concentrated cleaning solution to the strip as it moves through the second compartment into a third compartment.

25

mechanism in the third compartment for mechanically scrubbing the strip as it moves therethrough, means intermediate the said mechanical scrubbing mechanism for applying hot concentrated cleaning solution to the strip as the strip is scrubbed, mechanism for continuously recirculating the concentrated cleaning solution through the second and third compartments, means in the third compartment for rinsing the cleaned 10 and mechanically scrubbed strip with clean, cold wash liquid, vacuum-drying means in the third compartment for removing by suction at least substantially all liquid adhering to the strip without any appreciable evaporation of the liquid, the strip thereby passing dry and mechanically clean into a fourth compartment, means for washing the strip in the fourth compartment with clean hot wash liquid, the resulting cleaned strip passing from the fourth compartment into a fifth compartment, means in the fifth compartment for spraying the strip with high pressure sprays of cold wash liquid, and final vacuum-drying means in the fifth compartment for removing all adhering liquid from the strip.

GEORGE M. CROFT.
